COMBINED AERATOR AND DRINKING FOUNTAIN ATTACHMENT FOR FAUCETS AND THE LIKE

Buckley Crist, Plainfield, N.J., assignor to Jaclo, Inc., Brooklyn, N.Y., a corporation of New York

Filed July 3, 1968, Ser. No. 12,626

Term of patent 14 years

Int. Cl. D23—01

U.S. Cl. D23—35

FIG. 1

FIG. 2

FIG. 3

FIG. 5

FIG. 1 is a plan view of the combined aerator and drinking fountain attachment for faucets and the like embodying my design,

FIG. 2 is a left side elevational view,

FIG. 3 is a front elevational view,

FIG. 4 is a right side elevational view, and

FIG. 5 is a bottom view.

I claim:

The ornamental design for a combined aerator and drinking fountain attachment for faucets and the like, substantially as shown.
